United States Patent Office

Des: 228,800
Patented Oct. 23, 1973

228,800

VOTING MACHINE

Michael Terrance Moldovan, Jr., Lakewood, N.Y.,
assignor to AVM Corporation, Jamestown, N.Y.

Filed Sept. 22, 1971, Ser. No. 182,933

Term of patent 14 years

Int. Cl. D10—99

U.S. Cl. D52—2 R

Fig. 1

Fig. 2.

Fig. 3.

FIG. 1 is a front perspective view of a voting machine showing my new design in a closed position;

FIG. 2 is a rear perspective view thereof; and

FIG. 3 is a front perspective view thereof with the cover in open position.

I claim:

The ornamental design of a voting machine, substantially as shown and described.
